X-RAY TUBE

William H. McCurdy, Bloomfield, N. J., assignor,
by mesne assignments, to Westinghouse Electric and Manufacturing Company, East Pittsburgh, Pa., a corporation of Pennsylvania

Application May 25, 1935, Serial No. 23,463

7 Claims. (Cl. 250—35)

My invention relates to X-ray tubes and particularly to what is known to the art as a double focus tube.

In the utilization of an X-ray tube for fluoroscopic examinations it is essential in order to obtain as much detail as possible that the focal spot be of small area. Thus the area of the tungsten target portion of the anode which is impinged by the electrons coming from the thermionic cathode is comparatively small with the result that the generated X-rays are also confined to a small narrow beam producing desired detail and definition upon a fluorescent screen. Accordingly in order to produce a small fine focus the discharge current required for energization of the X-ray tube is relatively small.

However, in the making of radiographic exposures it is necessary that a large focal spot be produced upon the surface of the anode with a resultant increase in area of the emitted X-ray beam as well as the discharge current for the X-ray tube. This has usually necessitated the employment of two X-ray tubes with the normal X-ray equipment, one tube being utilized for the making of fluoroscopic examinations and the other for radiographic exposures. It has also been proposed in the prior art to provide a double focus tube wherein separate thermionic cathodes are utilized which are alternately energizable from an appropriate source of heating current. Such cathodes are naturally of different size and design and may require heating current of different magnitude in order to utilize maximum available discharge current without destruction of the anode surface when changing from one focal area to the other.

The difference in cathode heating current necessitates two separate sources of different magnitude each of which are connected to the respective cathodes. As a low tension heating transformer is usually employed for supplying the cathode heating current and the secondary winding thereof is so connected to the respective cathodes as to supply the separate current to the respective cathodes it is by no means an uncommon occurrence for an operator to supply the smaller cathode with excessive current. This may result in the cathode being disrupted but is more apt to destroy the small focal area of the anode. Again while it has been proposed to provide means whereby an operator can discern which of the two cathodes is connected to the heating source such indicator is difficult to observe at an appreciable distance from the X-ray tube.

It is accordingly an object of my present invention to provide an X-ray tube of the double focus type wherein an indication is given to an operator which is observable at a considerable distance that the smaller cathode is connected to the source of cathode heating current and the possibility of supplying an excessive current to the smaller cathode is eliminated as well as the preclusion of destruction of the small focal area of the anode.

Another object of my invention is the provision of an X-ray tube of the double focus type wherein either of the thermionic cathodes may be alternately connected to a source of heating current, and when the smaller cathode is so connected means which are carried by the X-ray tube gives a visual indication observable at considerable distance that the smaller cathode is energized and this means also prevents excessive heating current from being supplied to the smaller cathode thus precluding an attendant increase in discharge current and a destruction of the small focal area of the anode.

Another object of my invention is the provision of an X-ray tube of the double focus type having a cathode terminal in the form of a switch which is operable to selectively connect each of the thermionic cathodes to a source of heating current, and a resistance is carried by the cathode terminal which in one position of the switch connects the resistance in series with the smaller cathode and the source of heating current for the purpose of giving a visual indication observable at a considerable distance from the tube that the smaller cathode is energized and also to limit the current supplied to the small cathode to prevent an increase in the discharge current with a resulting destruction to the small focal area of the anode.

A further object of my present invention is the provision of an X-ray tube of the double focus type having a cathode terminal constituting a two position switch for selectively connecting each of the thermionic cathodes to a source of heating current and wherein an incandescent lamp is carried by the cathode terminal which in one position of the switch is connected in series with the smaller cathode for the purpose of giving a visual indication observable at a distance that the smaller cathode is energized from the source of heating current and also to limit the current supplied to the small cathode to prevent an increase in the discharge current with a resulting destruction to the small focal area of the anode.

Still further objects of my present invention will become apparent to those skilled in the art by reference to the following specification taken in conjunction with the accompanying drawing wherein,

Figure 1 is a side view of an X-ray tube of the double focus type provided with the conventional anode terminal and having one end of the tube broken away for simplicity, and constructed in accordance with my present invention.

Fig. 2 is a sectional view of the cathode terminal of the X-ray tube constructed in accordance with my present invention and taken on the line II—II of Fig. 1.

Fig. 3 is a sectional view of the cathode terminal taken on the line III—III of Fig. 2.

Fig. 4 is a sectional view of the cathode terminal of my present invention taken on the line IV—IV of Fig. 3, and

Fig. 5 is a diagrammatic illustration of the electrical connections of the X-ray tube cathodes together with a schematic showing of various portions of the cathode terminal.

Referring now to the various figures in detail I have shown an X-ray tube having the usual evacuated envelope 5. An anode electrode 6 is provided interiorly of the envelope in the usual manner and secured to the oppositely disposed reentrant portion of the envelope is a metallic shield 7 having elongated concave recesses 8 and 9 of different length and depth provided in the face of the shield which projects toward the anode to form focusing cups, as can be more appreciated by reference to Fig. 5. Disposed within the smaller recess 8 is a thermionic cathode in the form of a coiled tungsten filament 10 for producing a small focal area and similarly within the larger recess or focusing cup 9 is a longer coiled filamentary cathode 12 which is spaced closer to the adjacent anode surface for producing a larger focal area.

One end of each of the thermionic cathodes 10 and 12 is connected to the metallic shield 7 which latter is in turn connected by a leading-in conductor 13 extending through the reentrant portion of the envelope to a contact terminal 14 provided on the exterior of the envelope. Leading-in conductors 15 and 16 likewise extend through the envelope and connect the remaining end of the respective cathodes 10 and 12 to contact terminals 17 and 18, respectively, disposed in juxtaposition to the contact terminal 14.

Slidably engaging the three contact terminals 14, 17 and 18 is a cathode terminal which comprises a block of insulating material 19 provided with recessed metallic sleeves 20, 22 and 23 (Fig. 2) establishing electrical contact with the respective terminals 14, 17 and 18. A retaining screw 24 has its head recessed within the face of the block 19 adjacent the X-ray tube, which projects beyond the opposite face of the block 19, and a metallic strap 25 interconnects the metallic sleeve 20 and the screw 24, being held under the screw by a locknut or the like 26 and secured to the sleeve 20 in any suitable manner, such as by a screw 27, thus forming a continuous electrical connection. A conventional lamp socket 28 is provided in the periphery of the block 19 which is adapted to threadedly receive a suitable incandescent lamp 29 for a purpose to be hereinafter more fully described.

A metallic strip 30, similar to the strip 25, is secured to the metallic sleeve 22, such as by a screw 32, and extends a short distance across the surface of the block 19 where it is then angularly bent and protrudes within a recess 33 provided in the block 19 to thus form a spring contact for one terminal of the lamp 29. The socket 28, which is engaged by the shell of the lamp base, is connected by a suitable conductor 34 to an offset spring contact member 35 secured to the surface of the block 19, as can be more readily seen in Figs. 3 and 4.

Likewise an offset spring contact member 36 is connected, by means of a set screw or the like 37, to the metallic sleeve 23. For the purpose of enclosing the various spring contact members 35 and 36, as well as completing the switch elements for selectively connecting the cathodes 10 and 12 to a suitable source of heating current, such as a low tension transformer 38, an insulating sleeve 39 fits loosely over the protruding end of the elongated screw 24 which sleeve has a portion of reduced diameter to form a shoulder 40.

A metallic disc 42 fits upon the larger diameter portion of the sleeve 39 and bearing against the periphery of this disc as well as the block 19 is a rotatable spider 43 having a pair of radial arms 44 and 45 which alternately establish "wiping" engagement with either of the spring contact members 35 and 36 depending upon the direction of rotation of the spider. A pin 46 protrudes from the face of the block 19 which is contacted by either of the radial arms 44 and 45 thus limiting maximum rotation of the spider in either direction to approximately 30°.

A metallic spring plate 47 rests against the shoulder 40 of the sleeve 39 and presses against the member 42 to hold the spider 43 in place and in order to also maintain the spring plate 47 in place a further insulating block 48 is carried by the screw 24. The flat surfaces of this insulating block 48 are provided with metallic plates 49 and 50 and interposed between the plate 50 and the spring plate 47 is a metallic spring washer 52.

Similarly a metallic spring washer 53 bears against the metallic surface of the block 48 and the entire assembly is held in place through the medium of a nut 54 engaging the end of the elongated screw 24. The metallic plates 49 and 50 are flared inwardly to form suitable recesses between the adjacent spring washers 52 and 53, respectively, to thus form a receptacle for the engagement of a plug 55 connected to the cathode heating source or transformer 38. Due to the tension of the spring washers 52 and 53 upon tightening of the nut 54, not only are the various parts of the cathode terminal maintained as an integral unit, but the insulating block 48 although reasonably rigid can nevertheless be rotated about the elongated screw 24 and sleeve 39 with the plug 55 thus following rotation of the block 48 to prevent straining or tangling of the conductors from the low voltage transformer.

It will thus be observed that one conductor 56 extending from the transformer 38 is connected directly to the plate 49 and spring washer 53 by the engagement of one of the prongs of the plug 55. The nut 54 bearing against this washer 53 thus transmits the current to the elongated bolt 24, and the interconnecting metallic strap 25 in turn transmits this current to the recessed metallic sleeve 20, which is engaged by the contact terminal 14, and consequently to the cathode shield 7 through the conductor 13, to which one end of both thermionic cathodes 10 and 12 are connected. The remaining conductor 57 extending from the source or transformer 38 is similarly connected by the other prong of the plug 55.

55 to the plate 50 and spring washer 52 which latter being in contact with the metallic spring plate 41 thus transmits the current to the metallic disc 42 and spider 43.

5 When the spider is in the position shown in Figs. 3 and 4 the radial arm 45 contacts the offset spring contact member 35 which is connected by the conductor 34 to the shell of the socket 28, while the other arm 44 bears against 10 the pin 46.

The current after passing through the incandescent lamp 29 then passes through the spring contact 30 to the recessed metallic sleeve 22 and the conductor 15 which is connected to the contact terminal 17 and the remaining end of the smaller cathode 10 by the conductor 15. Accordingly with the switch in the position shown in Figs. 3 and 4 with the radial arm 45 of the spider 43 in contact with the terminal 35 not only is the smaller cathode 10 connected to the source of heating current or transformer 38 for the production of a small focal spot but the incandescent lamp 29 is connected in a series circuit with this cathode 10 and the source 38. Inasmuch as the lamp naturally has inherent ohmic resistance it functions to limit the magnitude of the current supplied to the small cathode 10 and thus precludes the possibility of excessive heating current, such as all that is available from the 30 transformer 38, being inadvertently supplied to the small cathode. This naturally would otherwise cause an increase in the discharge current when the tube is energized with resulting destruction to the small focal area of the anode. Moreover, the incandescent lamp when illuminated by 35 operation of the switch gives a visual indication observable by an operator at a considerable distance from the X-ray tube that the small cathode is energized thus showing the same is functioning and producing the desired focal spot for the appropriate examination.

A still further advantageous feature in the utilization of the incandescent lamp 29 resides in the fact that the energy consumed thereby is 45 readily dissipated in the form of heat to the surrounding atmosphere thus preventing such heat from otherwise causing deterioration of the insulating material of which the greater portion of the cathode terminal is composed.

50 The spider 43 is provided on its outer periphery with a metallic ring 58 having indicium thereon as can be seen from Fig. 1, which aligns with an arrow 59 provided on the periphery of the block 19. Accordingly when it is desired to alter the 55 focal spot for the purpose of making a radiographic exposure the switch or spider 43 is rotated in a counter-clockwise direction, as viewed from Fig. 4, until the indicia "large" aligns with the arrow 59 shown in Fig. 1. This will then 60 move the radial arm 45 out of contact with the offset spring contact terminal 35 against the pin 46 and at the same time the radial arm 44 will be moved away from this pin 46 into engagement with the offset spring contact terminal 65 36 as shown by the dotted lines in Fig. 4.

The current through the incandescent lamp 29 and the smaller cathode 10 will thus be interrupted and in lieu thereof current will then be supplied from the spider 43 to the spring contact 36 and recessed metallic sleeve 23, and through the contact terminal 18 and conductor 16 to the other end of the larger cathode 12. In this position of the switch the maximum current from the heating source is therefore supplied directly to the larger of the thermionic

cathodes with the result that when the X-ray tube is energized by high potential, the ensuing discharge current will be higher and due to the design of this larger cathode 12 together with the focusing cup 9 a larger focal spot is produced upon the anode surface as required for this particular type of examination.

5 It is also frequently desirable to limit the current supplied by the source to either of the cathodes and that the same be adjustable from time to time. In this event a variable resistance 10 60 is provided on the conventional control stand which usually encases the cathode heating transformer and is permanently connected in series with the primary winding of the heating transformer 38 and with either of the supply conductors leading from the usual commercial source of electrical energy.

15 It thus becomes obvious to those skilled in the art that I have provided an X-ray tube of the double focus type wherein the same is provided with means forming a cathode terminal, which are operable to alternately connect either of the thermionic cathodes to a source of heating current. Moreover an incandescent lamp is provided which functions for the dual purpose of giving a visual indication observable at a considerable distance from the machine that the small cathode is energized and which also precludes excessive current from being inadvertently 25 supplied to the cathode for producing the small focal spot with the result that the discharge current is prevented from increasing and causing a destruction of the small focal area of the anode. 30

35 Although I have shown one specific embodiment of my present invention I do not desire to be limited thereto as various other modifications thereof may be made without departing from the spirit and scope of the appended claims.

40 What is claimed:

1. An X-ray tube comprising an evacuated envelope, an anode electrode in said envelope, a pair of thermionic cathodes adapted to be heated to incandescence independently of each other disposed in said envelope for producing dissimilar focal spots, means surrounding each of said cathodes for focusing a discharge therefrom upon different size areas of the surface of said anode, means operable to selectively connect each of 45 said cathodes to a source of heating current, and means operable upon operation of said last mentioned means to give a visual indication observable at considerable distance that current is supplied to said cathode which produces the 50 smaller focal spot and to simultaneously limit the current supplied to such cathode to prevent a resulting increase in discharge current supplied to said X-ray tube with attendant destruction of the small focal area of said anode. 55

60 2. An X-ray tube comprising an evacuated envelope, an anode electrode in said envelope, a pair of thermionic cathodes adapted to be heated to incandescence independently of each other disposed in said envelope for producing dissimilar 65 focal spots, means surrounding each of said cathodes for focusing a discharge therefrom upon different size areas of the surface of said anode, means carried by said X-ray tube and operable to selectively connect each of said cathodes to a 70 source of heating current, and means carried by said last mentioned means and operable upon operation thereof to give a visual indication observable at considerable distance from said tube that current is supplied to said cathode which 75

produces the smaller focal spot and for simultaneously limiting the current supplied to such cathode to prevent a resulting increase in X-ray tube discharge current with attendant destruction of the small focal area of said anode.

3. An X-ray tube comprising an evacuated envelope, an anode electrode in said envelope, a pair of thermionic cathodes adapted to be heated to incandescence independently of each other disposed in said envelope for producing dissimilar focal spots, means surrounding each of said cathodes for focusing a discharge therefrom upon different size areas of the surface of said anode, and means carried by said tube operative to selectively connect each of said cathodes to a source of heating current and for giving a visual indication observable at considerable distance from said tube that current is supplied to said cathode which produces the smaller focal spot in one position of said last mentioned means as well as for simultaneously limiting the current supplied to the smaller focal spot producing cathode when connected to said source of heating current to prevent an increase in the X-ray tube discharge current with attendant destruction of the focal area of said anode.

4. An X-ray tube comprising an evacuated envelope, an anode electrode in said envelope, a pair of thermionic cathodes adapted to be heated to incandescence independently of each other disposed in said envelope for producing dissimilar focal spots, means surrounding each of said cathodes for focusing a discharge therefrom upon different size areas of the surface of said anode, and a cathode terminal for said X-ray tube including means operable to selectively connect each of said cathodes to a source of heating current and means operable upon operation of said last mentioned means in one position to give a visual indication observable at a considerable distance from said X-ray tube that current is supplied to said cathode which produces the smaller focal spot and to simultaneously limit the current supplied to such cathode to prevent an increase in the X-ray tube discharge current with attendant destruction of the focal area of said anode.

5. An X-ray tube comprising an evacuated envelope, an anode electrode in said envelope, a pair of thermionic cathodes adapted to be heated to incandescence independently of each other disposed in said envelope for producing dissimilar focal spots, means surrounding each of said cathodes for focusing a discharge therefrom upon different size areas of the surface of said anode, a switch carried by said X-ray tube and operable to selectively connect each of said cathodes to a source of heating current, and a device adapted to be connected to one of said cathodes

and the source of heating current by operation of said switch in one position to give a visual indication observable at a considerable distance from said X-ray tube that current is supplied to the smaller focal spot producing cathode and said device being simultaneously operable to limit the current supplied to such cathode to prevent an increase in the X-ray tube discharge current with attendant destruction of the focal area of said anode.

6. An X-ray tube comprising an evacuated envelope, an anode electrode in said envelope, a pair of thermionic cathodes adapted to be heated to incandescence independently of each other disposed in said envelope, means surrounding each of said cathodes for focusing a discharge therefrom upon different size areas of the surface of said anode, a switch carried by said X-ray tube and operable to selectively connect each of said cathodes to a source of heating current, and an incandescent lamp carried by said switch and adapted to be connected to one of said cathodes and the source of heating current by operation of said switch in one position for the purpose of giving a visual indication observable at a considerable distance from said X-ray tube that the current supplied to one of said cathodes is so limited and to simultaneously limit the current supplied to one of said cathodes to prevent an increase in the X-ray tube discharge current with attendant destruction of the focal area of said anode.

7. An X-ray tube comprising an evacuated envelope, an anode electrode in said envelope, a pair of thermionic cathodes adapted to be heated to incandescence independently of each other disposed in said envelope, one of said cathodes being of materially shorter length and disposed further from said anode than the remaining cathode, means surrounding each of said cathodes for focusing a discharge therefrom upon different size areas of the surface of said anode, and means carried by said X-ray tube operable to selectively connect each of said cathodes to a source of heating current and operable in one position to interpose a current limiting device between said source of heating current and the cathode of shorter length to give a visual indication observable at a considerable distance from said X-ray tube that the cathode of shorter length is connected to said source of heating current and for simultaneously preventing excessive heating current being supplied to the cathode of shorter length with an increase in X-ray tube discharge current and destruction of the small focal area of said anode produced by said shorter cathode.

WILLIAM H. McCURDY.
